UNITED STATES PATENT OFFICE.

GEORGE F. DENNE, OF PULLMAN, ILLINOIS.

SIGN.

1,179,081.

Specification of Letters Patent. Patented Apr. 11, 1916.

Application filed May 28, 1915. Serial No. 30,900.

To all whom it may concern:

Be it known that I, GEORGE F. DENNE, a citizen of the United States, and a resident of Pullman, county of Cook, and State 5 of Illinois, have invented certain new and useful Improvements in Signs, of which the following is a specification.

My invention relates to signs, number plates and the like, and more particularly 10 to a transparent sign whereon indicia such as letters, numbers or characters are adapted to be displayed by disposing the sign in front of a suitable illuminant.

More especially my invention is applicable 15 for displaying the numbers of locomotives or engines upon the headlight. As is well known the number-plates on locomotives become sooted and fogged shortly after being cleaned, owing to the great quantity of soft 20 coal smoke and dust through which the locomotive passes and it frequently occurs that after a comparatively short run the number will be unreadable even in front of a high candle-power lamp owing to the oxidizing 25 effects of the coal and other gases.

It is therefore an object of my invention to provide a sign that is so constructed that it is unnecessary to repaint the sign, and the parts whereof are so assembled that the characters thereon will not wear off nor become 30 effaced from frequent cleaning.

Another object is the provision of a sign wherein the characters borne thereby are completely inclosed from the atmospheric 35 and similar elements and which has a smooth glazed outer surface so that it may be readily and easily cleaned.

Still further objects are the provision of a sign that is clear and distinct in outline so as 40 to be easy to read, is easy and simple to make, and is comparatively inexpensive to manufacture so that it may be retailed at a moderate price to the consumer.

I prefer to accomplish these objects and 45 others by the means and in the manner hereinafter fully described and as more particularly pointed out in the claims, reference being had to the accompanying drawings forming a part of this specification, wherein,

50 Figure 1 is a front elevation of my invention shown detached from its holder or supporting frame. Fig. 2 is an enlarged transverse section thereof taken on line 2-2, Fig. 1. Fig. 3 is a perspective view of the plates comprising my sign structure in superposed 55 positions about to be assembled.

Heretofore it has been found in making signs of this type the most brilliant effect is obtained by the use of a translucent plate such as glass, porcelain or the like upon 60 which the characters are painted with an opaque or nontranslucent material or compound so that the light waves from the illuminating element will pass through the unpainted portions. It has also been found 65 that when the sign is painted upon the polished surface of the plates the paint will soon wear off. I have ascertained after considerable experimentation that a ground glass or a glass treated with a sand-blast is 70 most effective in a sign of this character because of the diffusion of the light waves passing through the unpainted portions and further the paint thereon will more readily adhere to the roughened surface thereby 75 producing a sign of greater longevity.

In carrying out my invention I employ a front and a rear plate one of which is provided with a ground or sand-blast surface upon which the characters are painted or 80 stenciled. For the purpose of convenience I have shown in the drawings a glass front plate 5 of suitable dimensions preferably of rectangular shape and the rear surface whereof is treated with a sand-blast to render the same capable of diffusing the light waves passing therethrough. Upon this ground surface I stencil or paint the characters 85 6 it is desired to display in reversed order similar to type face and I prefer to form the characters by painting around each of the same so that only the ground glass portion of the shape of the character displayed will stand out boldly through the glass. The material I employ to paint the 90 characters I prefer to make of a mixture of varnish, litharge and lamp-black in order to render the painted surface opaque and so to provide a means for causing the adherence of the opposing or back plate of the 95 sign. This compound 7 is of an extremely sticky nature and I find it expedient to permit the same to become slightly dried so that it will be what is known as "tacky" and then superimpose upon the same the back- 100 ing plate 8 which is of transparent glass and of a length and width slightly less than the ground-glass front plate 5 in order that the latter will overlap the backing glass plate at all points upon its sides and ends 105 substantially as illustrated in Fig. 2 of the drawings. It is also desirable to provide a 110

ground or sand-blasted border 11 on one face of plate 8 substantially parallel with its edges and co-extensive with its sides and ends so when the plates are superimposed 5 the material 7 will readily adhere to the roughened portion and materially assist in uniting the two plates as well as sealing the edges thereof to keep out soot and the like.

Owing to the sticky, cementitious nature 10 of the compound 7 the superimposed back- ing plate 8 will readily adhere to the back- ing plate 5 and, as the compound has been permitted to become "tacky" before the superimposing takes place the compound 15 will not "spread" and disfigure the sign characters.

I prefer to place a filler 9 of cementitious nature in the groove of recess 10 formed around the sign plates so as to firmly cement 20 the edges together substantially as shown in Fig. 2 of the drawings and thereby prevent soot and other oxidizing matter getting between the plates and marring the same.

While I have herein illustrated and de- 25 scribed certain specific means for carrying out my invention, it of course will be obvi- ous, to others skilled in the art to which my invention pertains, that numerous modifica- tions and refinements of the structure dis- 30 closed are possible without materially de- parting from the spirit of my invention. For example, the rear plate may have its

front surface ground or sand-blasted and the characters painted thereon reversed, in which 35 event the front plate would be of transpar- ent glass and superimposed thereon and the ground or roughened border may be omitted if desired, or both plates may have ground surfaces and placed with these surfaces op- 40 posing each other. I therefore desire it un- derstood that all such changes are contem- plated within the scope of my invention as expressed in the appended claims.

What I claim as new is:—

1. A sign comprising a glass plate having 45 light diffusing means thereon, a coating of non-transparent cementitious material upon one of the surfaces of said plate, and a transparent glass plate superimposed there- 50 upon and adhering thereto by said material.

2. A sign comprising a glass plate having light diffusing means thereon, a coating of non-transparent cementitious material upon the light diffusing surface of said plate, and a transparent glass plate superimposed upon 55 said first mentioned plate and adhering thereto by said material.

Signed at Pullman, county of Cook and State of Illinois, this 25th day of May, 1915.

GEORGE F. DENNE.
